WARP TENSION BAR FOR KNITTING MACHINES

Peter J. Schoenster, Teaneck, N. J., assignor to
Alfred Hofmann & Co., West New York, N. J.,
a corporation

Application August 14, 1951, Serial No. 241,784

6 Claims. (Cl. 66—146)

1

This invention relates to tension and guide bars for warp knitting machines.

Warp tension bars have been proposed which are designed for use in high speed warp knitting machines. Such bars include as the tension control element thereof, extended sheets of thin gauge metal, which form a resilient cantilever for supporting the guide bar. With continuous sheets or strips of metal extending the length of the machine, it is rather difficult to insure precision control of the warp tension at all points along the length thereof.

Accordingly, an object of this invention is to provide improved warp tension means including resilient mounting means for the guide bar which may be precisely adjusted for desired yarn tensions at successive points along the length of the bar.

Another object of this invention is to provide improved warp tension means including spaced, individual resilient supports which mount the guide bar, each support being separately adjustable to vary the response thereof to tensile forces derived from yarns moving over the bar, whereby the quality of the knitted fabric may be controlled and selvage yarn tensions may be suitably adjusted.

The invention accordingly consists in the combination of elements and arrangement of parts as exemplified in the embodiment herein shown and described.

In the drawing; Fig. 1 is a top plan view of a warp tension bar embodying the invention; and Fig. 2 is a side elevational view thereof.

Referring in detail to the drawing, 10 designates a warp tension bar assembly embodying the invention. The same comprises a conventional support bar 11 mounted on a warp knitting machine and may be mounted in a manner to permit the same to be rocked or oscillated about its longitudinal axis. Extending at right angles to bar 11, in spaced parallel relation, are a plurality of similar arm members 12 which may be of inverted channel cross section. Each member 12 is secured at the inner end thereof to support bar 11 by means of a screw 13. The flange portions 14 of arms 12 extend slightly beyond the web portion 15 at the outer end thereof, to provide aligned, apertured ears 16.

A second arm member 17, also of inverted channel cross section, is articulated to each arm 12. The arm member 17 has its flange portions 18 slightly extended beyond the web portion 19, at the inner end thereof, to form aligned, apertured ears 20.

2

Each of the ears 20 is adapted to register with an ear 16 and a transverse pivot pin 21 passing through the registering pairs of ears, provides a pivotal connection between each pair of arms 12, 17. Means is provided for resiliently supporting one arm of each pair of articulated arms, relative to the other arm. To this end, there is provided a flat, strip spring 22 which is mounted on the underside of the web portion 15 of each arm 12. The spring 22 may be mounted for longitudinal movement, for the purpose hereinafter described, by forming a pair of longitudinally aligned slots 23 in the web portion 15 of each arm 12 and passing screws 24 through the slots and openings in spring 22. Thus, the springs 22 may be retained in selected longitudinal positions relative to arm 12.

The free end portion of spring 22 underlies the web portion 19 of arm 17, thereby resiliently supporting the arm 17 relative to arm 12. An elongated, light, somewhat flexible yarn guide bar 25 interconnects the outer ends of arms 17, being suitably secured to projecting web portions 19a thereof.

Yarn indicated by the dotted line y is adapted to move from reels, not shown, over the support bar 11 and guide bar 25, to be directed to the knitting elements of the machine, not shown. It is apparent, that with any change in the yarn requirement of the knitting elements, at various portions of the knitting cycle, proper tension will be maintained through the resilient support of the guide bar 25. Thus, with an increased demand for yarn, the arms 17 will be deflected downwardly as indicated by the dotted lines and with a decrease in demand for yarn y, the arms 17 will be restored to their normal position by the biasing action of springs 22. Thus, varying tensions of the moving yarns may be transmitted through the guide bar to the springs.

While the support bar 11 may be fixedly attached to the frame of the knitting machine, when bar 11 is mounted for rocking movement, the same may control the operation of braking means and reel drive mechanism, in a manner well known in the art and shown in Patent 2,521,218, assigned to the assignee of the instant application. In such case, if the yarn tension should exceed the capacity of the springs 22, support bar 11 will be rocked about the longitudinal axis thereof and thereby actuate reel control mechanism connected thereto.

The resilient capacity of individual springs 22 may be suitably varied by adjusting the longitudinal position of the springs and retaining the

springs in adjusted position by means of screws 24. Thus, the tension response along guide bar 25 may be varied to provide means for obtaining maximum quality control of the fabric being knitted or to provide differential yarn tensions at the selvage ends of the machine.

As various possible embodiments might be made of the above described invention, and as various changes might be made in the embodiment set forth, it is understood that all matter herein set forth or shown in the drawing, is to be interpreted as illustrative and not in a limiting sense.

Having thus described my invention, I claim as new and desire to protect by Letters Patent:

1. In a warp knitting machine, a support, a warp guide bar and means for mounting said guide bar on said support comprising a pair of interpivoted arms, one of said arms being connected to said bar and resilient means extending between said arms for resiliently supporting said arms relative to each other.

2. In a warp knitting machine, a support, a plurality of spaced parallel arms extending from said support, an arm pivoted to each of said first mentioned arms, a warp guide bar interconnecting said second mentioned arms, and a strip spring member extending between each pair of pivoted arms for resiliently supporting said arms relative to each other.

3. In a knitting machine as in claim 2, wherein said spring member is longitudinally movable relative to said pivoted pair of arms and means for retaining said spring member in adjusted longitudinal positions thereof.

4. In a warp knitting machine, an elongated support, a plurality of spaced parallel arms extending from said support, an arm articulated to each of said first mentioned arms, a warp guide bar interconnecting said second mentioned arms, and a strip spring member fixed to one of each pair of articulated arms and having a portion engaging the other of each pair of articulated arms to resiliently support said articulated arms relative to each other.

5. In a warp knitting machine as in claim 4, wherein said support may be rocked about the longitudinal axis thereof.

15 6. In a warp knitting machine, a support, warp tension means including a warp guide bar and means for mounting said guide bar on said support comprising a plurality of independent, spaced resilient means interconnecting said bar and said support at spaced intervals along said bar, and means on each of said resilient means for adjusting the resilient capacity thereof.

PETER J. SCHOENSTER.
